VALVE GRINDER

Original Filed Feb. 6, 1928 3 Sheets-Sheet 3

John Orwic

By *Clarence A. O'Brien*, Attorney

UNITED STATES PATENT OFFICE

JOHN ORAWIEC, OF CHICAGO, ILLINOIS

VALVE GRINDER

Application filed February 6, 1928, Serial No. 252,291. Renewed August 25, 1930.

The present invention relates to improvements in valve grinders and has reference more particularly to an improvement over the valve grinding tool embodied in my prior 5 Patent #1,591,400, granted July 6, 1926.

One of the important objects of the present invention is to provide a valve grinder which is of such construction as to permit the same to be efficiently used in instances where 10 the usual valve grinder is inaccessible, such as for example when attempting to grind the valve in the last cylinder that is located beneath or directly adjacent the dash board of certain types of vehicles.

15 A further object of the invention is to provide a valve grinder wherein the same includes a reversely twisted shaft with which cooperates a slidable hand grip to effect the oscillatory movement of the shaft during the 20 use of the tool whereby the valve will be properly ground.

Another important object of the invention is to provide an improved valve engaging 25 unit that includes a means whereby the tool can be effectively and efficiently used, regardless of the type of valve that is to be ground, means being provided for permitting the use 30 of the tool where the valve is formed with the usual slot in the upper face of the head thereof, as well as where the spaced pin holes are formed in the upper face of the head of the valve.

A still further object of the invention 35 resides in the provision of a valve grinder wherein the parts comprising the same may be readily and easily assembled or disassembled, and due to its construction, considerable time and labor will be saved in grinding valves of internal combustion engines.

40 A further object is to provide a valve grinder of the above mentioned character which is simple in construction, inexpensive, strong and durable, and further well adapted to the purpose for which it is designed.

45 Other objects and advantages of the invention will become apparent from the following description when taken in connection with the accompanying drawings.

50 In the accompanying drawings wherein

like reference characters indicate corresponding parts throughout the several views:

Figure 1 is a side elevation of the valve grinder embodying my invention, a portion of the knob being shown in section to more 55 clearly illustrate its connection with the spindle that is secured at its lower end of the twisted shaft.

Figure 2 is an enlarged sectional view 60 through the sectional outer casing of the slidable hand grip showing the mounting for the shank engaging rollers.

Figure 3 is a transverse section taken substantially on the line 3—3 of Figure 2.

Figure 4 is an enlarged detail view of the 65 valve engaging unit, parts being shown in section.

Figure 5 is a fragmentary detail perspective view of the upper portion or head of the cylinder block engaging tripod, the 70 sleeve being removed.

Figure 6 is a side elevation of the valve 75 engaging means, the same being shown for use in conjunction with the type of valves that are formed with spaced slots or cylinders in their upper faces.

Figure 7 is an elevational view of the valve grinder showing an additional unit associated therewith when the valve grinder is used in grinding the rearmost valve on certain 80 types of vehicles.

Figure 8 is a detail of the detachable unit, parts being shown in section.

Figure 9 is a perspective view of the dash board engaging arm that cooperates with 85 the unit shown in Figure 8, and

Figure 10 is a detail perspective view of the knurled sleeve.

In the drawings wherein for the purpose of illustration is shown the preferred embodiment of my invention, the numeral 1 designates a flat iron shaft that is adapted for vertical disposition when in use. This shaft is twisted throughout its entire length and the shaft is provided with a pair of substantially diametrically opposed ribs 2 and 3 that extend from one end of the shaft to the other. Special attention is directed to the fact that the ribs are twisted spirally, but the direction of the twist of the spiral 95 100

is reversed at equi-distant longitudinally spaced points. As this construction has been more fully disclosed and defined in my prior Patent #1,591,400 a further description 5 thereof in the present instance is not thought necessary. It is to be observed however, that the reversed ribs are shorter.

A spindle 4 is slotted at its lower end for engagement over the upper end of the shaft

10 1 and a pin 5 extends through suitable registering openings formed in the slotted lower end of the spindle and the upper end of the shaft for securing the spindle on said shaft. A handle comprising a wooden knob 6 is, 15 formed with a central socket that extends upwardly from the bottom of said knob and arranged in this socket is the sleeve 7 for receiving the upper portion of the spindle 4. A tit 8 is associated with this sleeve 7 and 20 the same is operable within an annular groove 9 formed in the upper end portion of the spindle 4 for the purpose of preventing the displacement of the wooden knob from the spindle.

25 Suitable ball bearings 10 are provided in the upper closed end of the sleeve for cooperation with the upper end of the spindle 4 whereby said handle is free to rotate about the spindle.

30 The present invention further comprehends the provision of a valve engaging unit designated generally by the numeral 11, and the same comprises a sleeve 12 that is formed with longitudinal diametrically opposed 35 slots 13, the lower portion of the sleeve being externally threaded as clearly illustrated in Figures 1 and 4 of the drawings.

The upper end of this sleeve 12 is detachably secured to the lower end of the twisted 40 shaft 1, and to this end, there is provided at the upper end of the sleeve a socket 14 for the reception of the reduced lower end of the shaft. A rotatable band 15 encircles the socket 14 and this band is formed with 45 communicating openings of different diameters as clearly shown in the dotted lines in Figure 4 for the purpose of cooperating with the ball 16, whereby when the ball is disposed in the smallest one of the communicating 50 openings formed in the band 15 a positive lock between the lower end of the twisted shaft 1 and the sleeve 12 of the valve engaging unit 11 is afforded. Manifestly when the ball is in engagement with the 55 larger of the communicating openings in the band 15, the unit 11 may be readily disengaged from the lower end of the spirally twisted shaft.

Slidable within the sleeve 12 is the substantially U-shaped member 17, the same being formed at its upper end with the outwardly extending ears 18 that are operable within the respective diametrically opposed guide slots 13 to determine the pressure in 60 pounds. An expansible coil spring 19 is also

arranged within the sleeve 12, and the same is disposed between the socket 14 and the crown portion of the U-shaped member 17 in the manner as clearly illustrated in Figure 4. The purpose of this coil spring 19 is to normally exert a yielding pressure upon the U-shaped member 17 and also upon the shank 20, whose upper end portion is slidable in the lower end of the sleeve.

The U-shaped member 17 has its base or crown portion resting upon the upper end of the shank and a cross pin 21 extends through the upper end of the shank and has its ends extending into the respective guide slots as also clearly shown in Figure 4.

The lower end of the shank is forked and a pin 22 extends transversely through the outer end portions of the furcations 23 for a purpose to be presently described.

A blade 24 is pivotally mounted on the pin 22 between the furcations 23 of the forked lower end of the shank 20 and when the blade is disposed in the manner as shown in Figures 1 and 7, the same is to be used in conjunction with valve heads having slotted upper faces. However, when the valve grinder is to be used in conjunction with valves provided with the so called pin holes, the blade 24 is swung on its pivot so as to dispose the horizontally sliding arms 25 and 26, respectively, that are carried by the smaller end of the blade 24 outwardly of the forked lower end of the shank, as shown in Figure 6.

The smaller end of the blade is formed with a transverse slot to accommodate the inner opposed ends of the ends of the horizontally disposed arms 25 and 26, the outer ends of said arms being formed with laterally extending pointed dogs 27 that engage in the respective pin holes formed in the upper face of the valve that is to be ground. The slideable arms 25 and 26 are actuated by means of the curved links 28 and 29, the same being disposed on opposite sides of the blade 24. These links are pivotally secured at one end to the respective slideable arms 25 and 26 while the opposite ends of the links are operatively connected together by means of a pin 30 that is operable within a longitudinally extending slot 31 provided therefor in the larger portion of the blade 24.

The pointed dogs 27 are properly spaced apart by manually spreading the arms or moving the same inwardly toward each other.

For the purpose of supporting the pressure adjusting nut 32 above the cylinder block there is provided a tripod cross head washer 33. This washer is maintained in position upon the nut 32 by means of a spring locking ring 34. The cylinder block engaging legs are shown at 35 and three of such legs are provided. A ball bearing unit 36 is associated with the pressure adjusting nut 32 and the washer 33 to permit the free rotation of the nut and shaft, with exception of the washer

84. By raising the adjusting nut on the threaded sleeve 12, the legs 35 will also be moved upwardly in order to properly position the blade 24 or the dogs 27 with respect to the valve that is to be ground. Furthermore, by adjusting the nut 32 on the sleeve, the spring pressure upon the shank 20 may be varied.

Cooperating with the pressure adjusting nut is a locking member 37 that encircles the sleeve 12 and is adapted to engage in a slot 38 formed in one side of the sleeve as clearly shown in Figure 4. This locking member is formed with an outwardly projecting portion 39 that normally extends through a slot 40 provided therefor in a knurled sleeve 41 that encircles the adjusting nut 32 and is held in position by means of the spring finger 42.

The locking member 37 is formed with an oblong slot whereby said locking member may be moved horizontally by pressing inwardly on the outwardly projecting portion 39 against the tension of the spring finger 42 so that the portion of the locking member that engages in the slot 38 formed in the sleeve 12 will be moved out of engagement therewith, and the outer end of the projecting portion 39 will be disposed in the vertical groove 40' formed in the inner face of the knurled sleeve 41.

Also, the nut may be turned to any desired position upon the sleeve 12 and by releasing the pressure on the projecting end 39 of the locking member 37, the same will again enter the slot 40 in the knurled sleeve 41 and thus secure the nut in its properly adjusted position against rotation. The sleeve 41 and nut 32 will rotate together as a unit.

Forming a salient part of the present invention is the provision of the slidable hand grip designated generally by the numeral 43. The hand grip includes a sectional outer casing, the complementary sections of which are designated by the numerals 44 and 45 respectively. A frame work also including detachably connected sections and designated generally by the numeral 46 is arranged within the outer casing for disposition around the spirally twisted shaft 1. A series of roller bearing cages 47 are pivotally associated with the frame 46 as at 48, four of such cages being employed, and the same being arranged in pairs. Each pair of cages are operatively connected together by means of a pivotal link connection designated at 49 with reference more particularly to Figure 2. An anti-friction roller 50 is journaled for rotation in each cage and manifestly as there are four cages, there will necessarily be four rollers. One pair of these rollers engage one side of the twisted shaft 1, while the opposite pair engage the other side of the shaft whereby to effect an oscillatory movement of the spirally twisted shaft during the sliding movement

of the hand grip 43 in the manner to be hereinafter more fully described.

The particular manner in which the rollers are mounted in their respective cages is clearly shown in Figures 2 and 3 of the drawings.

The sections 44 and 45 of the outer casing forming a part of the slidable hand grip 43 are formed at their upper ends with the complementary flanges 51 and 52 respectively around which is adapted to be snapped a locking ring 53 for holding the upper ends of the complementary sections of the outer casing together. The lower ends of the complementary sections 44 and 45 of the outer casing are also provided with cooperating securing elements 54' and 54'' for maintaining the same in locked or assembled relation as shown in the dotted lines in Figure 2, and said last mentioned locking means is released through the medium of the spring latch or a coupling 54.

The frame 46 that is disposed within the outer casing is locked against rotation with respect to the outer casing through the medium of pins 55 that extend downwardly from the upper ends of the complementary sections of the outer casing and which pins enter into suitable slots provided therefor in the outer edge of the ring 53 that is carried by the upper portion of the sectional frame.

A clutch unit 57 may be associated with the frame 46 which serves as a one-way motion of the shaft 1 upon the down stroke only or on the upstroke when the handle is turned upside down. This clutch may be actuated by a clutch lever, not shown, that extends through the outer casing for the purpose of rendering the clutch inoperative, whereby the shaft will turn on both strokes.

With reference now to Figures 7, 8 and 9, there is shown an elongated knurled sleeve 58 through which extends the shaft 59, the same being longer than the sleeve. The upper end of the shaft 59 is formed with a socket 60 for receiving the reduced lower end of the spirally twisted shaft 1, and this socket is notched as at 61, it being understood of course that the reduced lower end of the twisted shaft 1 is also formed with a notch for communication with the notch 61.

A tube 62 surrounds the upper projecting end of the shaft 59 and this sleeve is also formed with a slot that registers with the notch 61 and through which slot extends the laterally projecting end 63 of a spring finger 64 that is secured on the outer side of the tube. Normally, the inwardly projecting portion 63 of the spring finger is held in an inoperative position, and for the purpose of locking the inwardly projecting portion 63 in engagement with the notch in the lower end of the twisted shaft 1 when the same is disposed in the socket 60, I provide the sliding locking sleeve 65 that is movable along the

tube 62 over the spring finger 64 in the manner as more clearly illustrated in Figure 8.

This inwardly extending portion 63 of the spring finger 64 provide an operative connection between the lower end of the spirally twisted shaft 1 and the shaft 59.

A member 66 is operatively connected to the lower end of the shaft 59 that extends below the lower end of the sleeve 58 through the medium of a universal joint designated generally by the numeral 67 and this member 66 is so formed at its lower end as to cooperate with the socket formed in the upper end of the sleeve 12 of the valve engaging unit 11 in the same manner as the lower end of the spirally twisted shaft 1 engages with said socket. The unit shown in Figure 8 is only used for the purpose of grinding valves that are ordinarily inaccessible with the valve grinder shown in Figure 1 and frequently such valves are the ones located in the last cylinder of certain types of automobiles.

Cooperating with the unit shown in Figure 8 is an elongated lever 68, the same being formed at its upper end with an enlarged laterally extending ring 69 that slidably engages over the knurled sleeve 58. The lower end of this lever is curved in the opposite direction to provide a dash board engaging foot 70 and when the parts are arranged as shown in Figure 7 of the drawings, it will be readily observed that the ring 69 is canted, while the foot 70 engages the dash board A and the valve engaging unit 11 will be disposed upon the top of the cylinder block B directly over the valve C and the spirally twisted shaft 1 will be disposed upwardly at an incline so that the same can be readily actuated to effect the operation of the shaft that is operatively connected to the valve engaging blade 24.

The operation of my improved valve grinder is thought to be readily obvious from the construction disclosed, and therefore a further detailed description thereof is believed unnecessary.

It will thus be seen from the foregoing description, that I have provided an improved valve grinder which will save considerable time and labor in grinding valves of internal combustion engines, and furthermore by reason of the detachable units above described, valves that are ordinarily inaccessible can be readily and easily reached so as to insure the positive and efficient grinding of such valves with my improved tool.

While I have shown the preferred embodiment of my invention, it is to be understood that various changes in the size, shape and arrangement of parts may be resorted to without departing from the spirit of the invention and the scope of the appended claim.

Having thus described the invention, what

I claim as new and desire to secure by Letters Patent is:—

In a valve grinder, a shank formed with a fork at its lower end, a blade pivoted intermediate its ends in the forked lower end of said shank, a valve slot engaging element formed on one end of the blade, the other end portion of the blade being provided with a transverse slot, a pair of co-acting horizontally adjustable arms slidably disposed at their inner ends in said transverse slot, the outer ends of the arms being disposed laterally to form pin hole engaging elements, a pair of curved links pivotally connected at one end to the outer end portions of the respective arms, said curved links being disposed on opposite sides of the blades and connected together at their opposite ends, the blade being formed with a longitudinal slot to accommodate the connection between the adjacent ends of the curved links, the valve slot engaging element of said blade being disposed within the forked lower end of said shank when said pin hole engaging elements are in use, and vice versa.

In testimony whereof I affix my signature.

JOHN ORAWIEC.
